UNITED STATES PATENT OFFICE.

ARTHUR W. HAWKINS, OF MUSKEGON, MICHIGAN, ASSIGNEE TO CHICAGO RAILWAY EQUIPMENT COMPANY, OF CHICAGO, ILLINOIS, A CORPORATION OF ILLINOIS.

ADJUSTABLE CHAIR.

Application filed February 27, 1925. Serial No. 11,978.

This invention relates to new and useful improvements in adjustable chairs or supports for brake beams, the object being to provide a chair member carried by a brake beam part and adjustable in vertical plane to bring it in proper operating engagement with a corresponding track member or safety bar affixed to a car truck part.

Further objects of the invention are to provide a chair member consisting of two elements attached to each other, one of said elements operatively engaging a brake beam part and the other having engagement with a support on car truck, said elements being adjustable in relation to each other in order to positively vary in vertical plane the points of engagement of said elements with the respective parts.

Still further objects of the invention are to provide a chair member for brake beams, said chair member being provided with an element positively adjustable relative thereto in vertical plane, and means for securing said element in its adjusted position.

With these and other objects in view, my invention consists in certain novel features of construction and arrangement of parts, hereinafter more fully described and claimed, and illustrated in the accompanying drawings, in which—

Figure 1 is a cross sectional view through a brake beam and a car truck part and showing the chair in operative engagement therewith.

Figure 2 is a vertical cross section through the chair and showing the same attached to a brake beam part.

Figure 3 is a side elevational view of the chair.

Figure 4 is a horizontal cross section taken on line 4—4 of Figure 2.

Figure 5 is a fragmental sectional view of a modified form of chair.

Figure 6 is an end elevational view of another modified form of chair.

Figure 7 is a side elevational view of same.

Figure 8 is a horizontal cross section taken on lines 8—8 of Figure 6.

Figure 9 is a vertical cross section through a brake beam and a car truck part and showing another modified form of a chair associated therewith.

Figure 10 is a vertical cross section taken through the form of chair shown in Figure 9.

Figure 11 is a side elevational view partly broken away of the same.

Figure 12 is an end elevational view of another modified form of brake beam chair.

Figure 13 is a side elevational view of same.

Figure 14 is a detail view of a modified form of the plunger or shoe member adapted to be used in connection with my adjustable chair.

Figure 15 is a side elevational view of another form of adjustable chair.

Figure 16 is an end elevational view of same.

Figure 16^a is a sectional detail view of a modified form of adjustable chair.

Figure 17 is a side elevational view of another form of chair.

Figure 18 is a top plan view of the chair shown in Figure 17.

Figure 19 is a perspective detail view of the shoe member used in said chair.

Figure 20 is a perspective detail view of a locking member used in conjunction with said shoe member.

Figure 21 is a side elevational view of another modified form of chair.

Figure 22 is a vertical cross section taken on lines 22—22 of Figure 21.

Figure 23 is a side elevational view of another modified form of brake beam chair.

Figure 24 is a sectional view taken on lines 24—24 of Figure 23.

Figure 25 is a detail view of a modified form of shoe member.

Figure 26 shows another modified form of chair applied to a brake beam strut member.

Figure 27 is an enlarged sectional view of same.

Figure 28 is a front elevational view, and

Figure 29 is a top plan view of same.

It has been found in practice that there is a certain amount of variation in the individual truck assemblies which necessitates adjustment in vertical plane of either the brake support bar carried by a car truck part or the chair carried by the brake beam. The present invention relates to a chair adapted to be carried by a brake beam part and positively adjustable in vertical plane so as to bring said chair in proper operative engagement with the support bar, which latter can be either of the yielding type or the rigid type.

The chair consists of two pieces, one of

which is clamped to a brake beam part and the other, which engages the support or track bar, has a fixed engagement with the first piece and is adjustable relative thereto to vary the distance between the points of engagement of said chair with the brake beam part and the car truck part or safety support.

Referring by numerals to the accompanying drawings, 10 indicates a car truck part, in the present instance a spring plank, 11 indicates the compression member and 12 the tension member of a brake beam, and 14 is a track or support bar fixed to said car truck part and underlying said brake beam part to form an auxiliary support therefor. A chair 15 is carried by a brake beam part, such as the tension member 12, and rests on track 14 with which it has a sliding engagement. This chair comprises two elements, a clamp element 16 and a shoe member or plunger 17. Clamp member 16 has a seat 18 for receiving the brake beam part 12 and is provided with ears or extensions 19 which extend past said member 12 and are clamped together to secure said chair in position by a nut and bolt fastening 20.

Depending from clamp member 16 and formed integral therewith is a socket portion 21 having formed therein a vertically disposed socket 21^a in which is disposed the shank portion 17^a of shoe element 17. One side wall of socket member 21 is provided with a slot 22 terminating in outwardly and vertically disposed flanges 21^b which are formed integral with said side wall. An ear or extension 17^b is formed integral with shank portion 17^a and projects laterally therefrom and occupies slot 22. Flanges 21^b are provided with a plurality of coinciding apertures 23 in which is adapted to be seated a cotter pin or similar locking device 24. Extension 17^b is provided with an aperture 25 which is adapted to receive cotter pin 24, thereby locking the shoe member 17 to the clamp member 16. Apertures 23 are arranged so as to provide a suitable range of adjustment for the shoe member 17 and member 24 when seated in apertures 23 and the aperture 25 positively secures the shoe member in its adjusted position in member 16 so that the two chair elements possess the same rigidity and strength as a unitary structure.

In adjusting the shoe member 17, the same is moved outwardly or inwardly as may be desired in socket 21 and the aperture 25 is brought into alignment with the nearest pair of apertures 23, whereupon member 24 is inserted therethrough and secures said shoe member to the upper member 16.

In the form shown in Figure 5, the shank portion 17^a of the shoe member is provided in one side with a series of ratchet teeth 25 which are adapted to be engaged by the free end of a spring member 26, the opposite end

of which is anchored in the socket portion 21. Spring member 26 holds the shank portion 17^a against inward or upward movement and locks shoe member in adjusted position while the track member 14 on which said shoe member rests prevents the withdrawal thereof from the clamp member 16.

In the form shown in Figures 6 to 8, a clamp member 27 is clamped in position by suitable fastening devices 28 engaging extensions 29 and said clamp member is provided with lateral extensions or lugs 30 having vertically disposed openings 30^a which are traversed by upwardly extending members 31, the lower ends of which are formed integral with a shoe 32. Each member 31 is provided with a vertically disposed row of apertures 33 and extensions 29, which extend a suitable distance above lugs 30, are provided with aligned apertures 34 which are adapted to coincide with any pair of apertures 33 so that a cotter pin or similar member 35 can be inserted through said apertures and hold the shoe member 32 in fixed relation with clamp member 27. To adjust the chair, all that is necessary is to remove member 35 and move member 32 and extensions 31 in vertical plane so as to bring the brake beam part in proper elevation with respect to the car truck part whereupon member 35 is inserted through the proper apertures 33 of the shoe member which are brought into alignment with apertures 34 of the clamp member.

In the preceding forms just described, the shoe member is capable of adjustment without disturbing the fastening of the clamp member on the brake beam part, and means independent of the clamping means are used to fix the adjusted chair elements to each other.

In the form shown in Figures 9 to 11, a clamp member 36 is secured in position on the brake beam part by suitable fastening devices consisting of a bolt 37 and nuts 38. A shoe 39 is carried by the lower end of one of a pair of vertically disposed plates or extensions 40, the lower end of the opposite plate being hinged to the first plate as indicated at 41. These plates are provided with vertically and centrally disposed slots 42 for accommodating bolt 37 which passes therethrough. The opposed inner faces of plates 40 are provided with a series of horizontally disposed coinciding grooves 40^a which are adapted to form seats for ribs 36^a horizontally formed on clamp member 36. Thus by loosening bolts 38, plates 40 can be swung outwardly so that they clear ribs 36^a whereupon said plates and shoes 39 can be moved upwardly or downwardly as desired. When shoe 39 occupies the desired position, plates 40 are moved inwardly so as to bring grooves 40^a nearest to ribs 36^a in engagement therewith whereupon nuts 38 are tight.

ened so as to lock the adjustable chair element to the clamp member 36.

The form shown in Figures 12 and 13 is similar to the form shown in Figure 6 in that a clamp member 44 is provided with side lugs 45 having vertically disposed openings therein through which pass the upwardly presented parallel members 46 of a shoe 47. However, only one securing device is used to clamp member 44 in position on the brake beam part and fix shoe member 37 in its adjusted position. This fastening device comprises a bolt 48 which passes through the apertures formed in extensions 46 of the shoe member and the apertures formed in extensions 44^a of the clamp member and which receives a nut 48^a and a lock nut 48^b.

In the form shown in Figure 14, a shoe member 49 is provided with upward extensions 49^a having two vertically disposed rows of apertures 49^b, the apertures of one row being arranged intermediate the apertures of the other row or in staggered relation with each other so as to permit greater range of vertical adjustment.

The form illustrated in Figures 15 and 16 comprises a shoe member 50 having upward parallel extensions 51 which extend upwardly from each side of tension member 12. Said extensions 51 are provided with coinciding horizontally disposed slots 51^a which are adapted to receive the horizontally disposed legs 52 of a U-shaped member 53 which are disposed above and below tension member 12. The ends of portions 52 extend past the respective portion 51 and are apertured to receive a cotter pin or similar locking device 54 so as to prevent displacement of member 53. In this manner the shoe member 50 supports the brake beam part 12 and is held in engagement therewith. To effect vertical adjustment of the shoe member 50, end portion 51 is provided with a horizontal extension 55, the end of which terminates against the web portion of compression member 11. Member 55 is apertured and passing through this aperture is a bolt 56 the ends of which are seated in the ends of a U-shaped member 57 which is carried by compression member 11. Threaded on bolt 56 and engaging the opposite faces of member 55 are nuts 58. Thus by turning nuts 58 in the proper direction, shoe 50 can be adjusted in vertical plane.

In the form shown in Figure 16^a, a spring 26^a is provided with a pawl 26^b which extends through socket 21 and engages the teeth of shank 17^c. The end of this spring is slightly turned outwardly as indicated at 26^e whereby said spring can be manually engaged to move pawl 26^b out of engagement with said teeth.

The form shown in Figures 17 to 20 comprises a horizontally disposed member 59 clamped at one end to the compression member 11 and reinforced at the other end by being rebent as shown at 60. The extremity of

the rebent portion is formed to engage tension member 12 and clamp it to member 59. The reinforced or double portion 60 is provided with an aperture 61 through which passes a shank portion 62 of a shoe member 63. One edge of shank portion 62 is formed with a plurality of horizontally disposed notches 62^a which are spaced at regular intervals and form seats for a plate 64 which is secured in position on double portion 60 by bolts or rivets 65 engaging apertures 64^a. This plate has one edge 64^b projecting in the plane of opening 61 for engaging one of the notches 62^a.

In the form shown in Figures 21 and 22, a member 66 is secured at one end to compression member 11 and has its opposite end rebent to form a seat 66^a for receiving the tension member 12. The rebent end lies flat on member 66 and a vertically disposed aperture 67 receives shank 68 of a shoe member 69. This shank is provided with a screw thread and screwed thereon is a pair of nuts 70, one above and one below the portions of member 66, whereby by turning said nuts in proper direction, shoe member 69 may be raised or lowered as desired. A washer 71 is preferably interposed between the upper nut and member 66. Shank 68 is also provided with a plurality of apertures 72 vertically disposed therein for receiving a cotter pin 73.

In the form shown in Figures 23 and 24, a member 74 is secured to compression member 11 and has one end bifurcated to form horizontally disposed spaced portions 75 arranged above and below the tension member 12. A shoe member 76 is provided with a pair of upwardly extending spaced portions 77, each of which is provided with a plurality of openings 78 arranged in a vertical row and adapted to receive portions 75 whereby shoe member 76 may be adjusted in vertical plane by seating portions 75 in corresponding openings 78. A member 79 is seated in the projecting ends of portions 75 and prevents the withdrawal of said portions from engagement with legs 77.

In Figure 25, a shoe member 80 is shown, but instead of being formed with an integral shoe, a roller 81 is journaled in the lower end of said member to form an anti-friction bearing.

Figures 26 to 29 show the chair as applied to a brake beam strut member. This strut member 82 is provided with bifurcated extensions 84 which carry a horizontally disposed pin 85. A chair piece 86 is mounted on said pin and terminates in a vertically disposed plate 87 provided with a vertically disposed row of apertures 88 for receiving a cotter pin 89 which is carried by a sleeve 90 of a shoe member 91. Sleeve 90 embraces the shank or plate 87 and is adjustable thereon so as to space said shoe member in vertical plane the proper distance relative to the brake

part 82. The two chair pieces are fixed to each other by cotter pin 89. To prevent rotation or rocking movement of piece 86 about the axis of pin 85 said piece is provided with an extension or enlargement 86^a which bears against said strut and holds said piece against displacement.

A chair of my improved construction is readily adjustable in vertical plane so as to obtain proper correlation of the brake beam with the parts associated therewith and is positively held in adjusted position in order to fix and maintain the chair in its adjusted position.

While I have shown and described various forms of the chair constructed in accordance with my invention, still other forms and modifications can be designed without departing from the scope of my invention.

I claim:

1. In adjustable third or fourth point support chair for a brake beam, a rigid member adapted to be fixed to a brake beam, and having a vertical recess with an opening in its side, there being a laterally extending perforated flange adjacent to said opening, a rigid member adapted to slide in said recess and having a laterally extending perforated ear, and an element for insertion through said ear and flange to hold said members in desired relation.

2. In adjustable third or fourth point support chair for a brake beam, a rigid member with a downwardly facing socket and clamp

jaws above the same, a rigid element slidably fitting in said socket, and cooperating means for holding said member and element in desired relation.

3. A brake beam chair comprising separately formed rigid elements, means for rigidly securing one of said elements to a brake beam, said elements having a plurality of interlocking parts for positively and adjustably securing said elements to each other.

4. A brake beam chair comprising a rigid element, a device for fixedly securing the same to a brake beam, another rigid element adapted to slidably engage a support arm, and means for adjustably and fixedly securing said elements to each other, said means including a plurality of seats arranged at different heights on one of said elements, and a coacting member mounted on the other of said elements.

5. In combination in a car truck, a brake beam support arm, a brake beam, a rigid chair element slidably carried on said arm, a second rigid chair element rigidly mounted on said brake beam, and interengaging parts on said chair elements, the parts on at least one of said elements being arranged in series at different levels for selective engagement with the part or parts on the other of said elements to vary the height at which said chair supports said beam from said arm.

In testimony whereof I hereunto affix my signature this 20th day of February, 1925.

ARTHUR W. HAWKINS.
